Theo. N. Vail

UNITED STATES PATENT OFFICE.

THEODORE N. VAIL, OF BOSTON, MASSACHUSETTS.

TELEGRAPH AND TELEPHONE LINE.

SPECIFICATION forming part of Letters Patent No. 279,289, dated June 12, 1883.

Application filed April 10, 1883. (No model.)

To all whom it may concern:

Be it known that I, THEO. N. VAIL, of Boston, in the county of Suffolk and State of Massachusetts, have invented certain Improvements in Telegraph and Telephone Lines, of which the following is a specification.

My invention relates to the construction of telegraph and telephone lines; and its object is to provide suitable devices whereby comparatively soft and non-tenacious metal wires may advantageously be employed without danger of breakage or of contact with one another.

It is well known to those skilled in the art of telegraphic and telephonic construction that iron has heretofore been almost exclusively used as a material for line-wire, although its electrical conductivity is not high, being, in fact, but one-sixth of that of a copper wire of the same size. The superior electrical properties of copper wire are and have long been well understood, and for protected wires—such as those used for internal construction, for submarine and aerial cables, and also for electrical apparatus—copper has uniformly been used. For line-wire, however, in spite of the electrical advantages of copper wire, it has until the present time been neglected, on account of mechanical disadvantages which have appeared insurmountable. These are, briefly, its lack of tenacity, its low breaking strain and feeble tensile strength, its excessive stretch, and non-elasticity. Experience has demonstrated that, in telephonic communication more especially, if the foregoing mechanical defects could be counteracted, copper conducting-wires would be very useful, on account of their low specific resistance.

My invention consists in combining with a stout and strong suspending wire or rod of iron or steel a number of light supporting racks or frames upon which any number of copper wires may be strung and supported, the suspending-wire being supported by posts or poles placed at the usual distance apart, and the supporting frames or racks being interposed between the said poles.

In the drawings which illustrate my invention, Figure 1 is a front view of one of the supporting-racks. Fig. 2 is a section of line-wire between two poles, showing the use of my invention; and Fig. 3 is a modification of the same, showing the supporting-line arranged

below the rack instead of above, as in Fig. 2.

The poles P carry the usual cross-arms, e, fitted with supporting-insulators in the usual way. In addition to the cross-arms, the poles also support a strong iron or steel wire, B, which runs from pole to pole, and may or may not be insulated. In the figure it is shown as being attached to the insulators f, and when so insulated it may be used as a conductor. I provide, also, and arrange in any desired number between the poles, light racks or frames made of wood, and consisting, as shown, of a series of cross-arms, b, fixed transversely to an upright, a. These are hung from the suspending-wire between the poles P, and serve both to support the wires and to prevent them from coming into contact with one another. The smaller wires w are of copper, or of any suitable alloy thereof, and are fastened to the insulators of both the poles P and racks A; or, if in some cases I prefer to dispense with the insulators, the said wires w may be fastened merely to the pins of the said poles and racks. As shown in Fig. 2, the suspending-wire may be supported by the top of the poles and allow the racks A to fall below it; or it may, as in Fig. 3, be attached to the pole at the lower point, and in such a case the rack A would be supported thereon. If many wires w were used, it would be found convenient to support the racks by a heavy wire at both top and bottom, and in the figure the racks are shown as being provided with holes d, whereby they may be attached to two of such suspending-wires. I may also, if I so elect, use more than one supporting-wire at either top or bottom. I may also construct the racks A with more than one upright a, thus adding strength to the frame.

It will be observed that the racks or frames A and the wires w are mutually dependent, the wires supporting the frames, and the frames both supporting and separating the wires, the whole being supported by and suspended from the heavy steel or iron wire B, which is supported only by the poles.

By my invention I am thus enabled to use copper or other wire of soft or non-tenacious character, but of high electric conductivity, and as copper has a specific conductivity which is much higher than iron I may use a small and light copper line-wire with as good results as would accrue from the use of a much

larger iron or steel conductor. Moreover, by the use of such small wires the weight upon the supports is greatly diminished, and an infinitely greater number of line-wires may be supported by the same poles than the said poles would otherwise be capable of carrying.

In practice the suspending-wire B may be of any suitable size—for example, No. 4 galvanized iron—and the conducting-wires w are of much smaller gage and lighter weight, varying, for example, from No. 14 to No. 20. I do not, however, confine myself herein to any special size or weight, since it is evident that both may be greatly varied without contravening the spirit of my invention, provided always that the suspending-wire is relatively larger and stronger than the suspended conducting-wires.

I am aware that it has heretofore been proposed to use intermediate supports for the line-wires between the fixed supports, being suspended from a strong wire or cable. I do not therefore lay claim to intermediate supports, broadly.

I claim—

1. In a system of electrical communication,

the combination of the conductors, the series of fixed supports—such as poles—provided with a separate pin or rest for each conductor, and the intermediate movable supports, also provided with a separate pin or rest for each conductor, substantially as described.

2. The combination, substantially as hereinbefore described, of a heavy suspending-wire of iron or steel, and a series of suitable supports or poles therefor, with a series of auxiliary supports consisting of light cross-arm carrying frames depending from and supported by the said heavy suspending-wire, and a series of relatively small conducting-wires of copper, brass, or other suitable low-resistance metal or alloy, the said conducting-wires being supported by and insulated from both main and auxiliary supports, for the purposes specified.

In testimony whereof I have signed my name to this specification, in the presence of two subscribing witnesses, this 4th day of April, 1883.

THEO. N. VAIL.
